UNITED STATES PATENT OFFICE.

LLOYD W. PRICE, OF ALVADO, OHIO.

MAIL-BAG CATCHING AND DELIVERING DEVICE.

1,265,111.

Specification of Letters Patent.

Patented May 7, 1918.

Application filed February 17, 1916. Serial No. 78,972.

To all whom it may concern:

Be it known that I, LLOYD W. PRICE, a citizen of the United States, residing at Alvado, in the county of Seneca and State 5 of Ohio, have invented certain new and useful Improvements in Mail-Bag Catching and Delivering Devices, of which the following is a specification.

My present invention has relation to certain new and useful improvements in mail bag catching and delivering devices; and as its primary object, it aims to provide a novel device of this nature to expedite the interchanging of the mail bags from the ground 15 device to the car device and vice versa, which will obviate excessive wear on the mail bags and at the same time effect the automatic interchanging thereof in a manner that will not endanger occupants of the 20 mail car or persons standing in the vicinity of the ground device.

A further object of my invention is to provide a device of the type in question that is extremely simple in construction, 25 strong and durable and highly practical from both the standpoint of the manufacturer and the standpoint of the user; and which, it is believed, may be manufactured at a comparatively low cost.

Various other objects and advantages will become apparent during the continuance of the following description.

These objects are accomplished by such means as are shown in their preferred form 35 in the accompanying drawings, described in the following specification and then more specifically pointed out in the appended claims.

In the accompanying drawings wherein 40 like characters designate like parts throughout the several views:

Figure 1 is a view in elevation showing the car device as in an operative relation to the ground device, such as occurs at the 45 time the car passes the ground device to effect the interchanging of the mail bags;

Fig. 2 is a view in top plan of the catching and delivering arm of the car device;

Fig. 3 is a view in top plan of the receiving 50 and delivering arm of the ground device;

Fig. 4 is a view in top plan of a delivering arm of the ground device;

Fig. 5 is a view in side elevation of a supporting arm for the car device; and

Fig. 6 is a view in detail showing the up-

per end portion of the supporting post for the ground device.

In reducing my invention to practice, I first provide a ground device that consists of a supporting post or standard 10 which carries at its upper end, a laterally projecting supporting arm 11, as at 12, the latter in turn supporting a pair of yoke arms 13 and 14 respectively, as at 15. The arms 13 and 14 are arranged in spaced relation to each other as shown in Fig. 6, whereby they serve to support both the receiving and delivering arm of the ground device and permit the passing of the delivering arm of the car device therebetween.

The delivering arm of the ground device, shown in detail in Fig. 4, consists generally of a body 16 to be formed of wood, metal or other material and attached to the upper arm 14 as at 17, the same being reduced at 70 its respective ends as at 18 and 19 for the purpose that will subsequently appear. A strip of metal or other material 20 has one end fixedly connected to one of the reduced portions 18 of the head 16 as at 21, while the said reduced portion also carries a second strip 22 to extend in parallelism to the aforesaid strip, the fastening means 21 also serving to retain the latter strip in a rigid position. As shown in Fig. 4, the strip 20 75 is of greater length than the latter strip; however, both strips are connected intermediate their ends by means of a block 23 thereby assuring their rigidity at all times.

Adjacent its free end, the strip 20 carries a pivoted catch 24 as at 25, one end of the catch normally lying in proximity to the strip 22, while the other end is normally held in spaced relation to the strip 20 80 through the instrumentality of a retractile spring 26. One end of the retractile spring 26 is connected to the outer end of the catch while the other end of the retractile spring has connection with the fastening member 27 at the free end of the strip 20 as shown. 85 Consequently in view of the fact that the strips 20 and 22 are in spaced relation, a ring or other mail bag carrying structure may be positioned therethrough and yieldingly retained in place through the instrumentality of the catch 24.

The opposite reduced portion 19 of the head 16 has connection with the respective ends of a metallic strip 28, as at 29, the intermediate portion of the said strip being 100 110

bent to form a handle 30. As clearly shown in Fig. 4, the handle 30 projects oppositely to the strips 20 and 22 thereby providing for the quick adjustment of the delivering arm or the removal of the same from the ground device, such as the case may be.

The lower arm 13 of the ground device carries a head 31 as at 32 (see Fig. 3) each end of the said head being reduced as at 33 and 34, similar to the head 16 above referred to. A metallic strip has its respective end portions attached to the reduced portion 34 of the head 31, as at 35, the intermediate portion of the strip forming the receiving arm 36. The other reduced portion 33 of the head 31 has connection with the ends of another strip of metal as at 37, while the intermediate portion of the last mentioned strip is bent as at 38 to provide a suitable hand grip.

In order to accommodate the movable keeper 39, the arm 36 above referred to is provided intermediate its ends with a transverse pindle 40, the ends thereof being attached to the said keeper as shown to pivotally mount the keeper, while a spring 41 is mounted upon the pindle and provided with an arm 41' engaging the keeper and having a normal tendency to retain the keeper in a raised position. Spaced collars 42 and 43 are slideable on the arm 36 and the keeper 39 whereby the latter may be normally retained in a closed or lowered position against the tension of the spring 41, the said collars being connected by strips 44 and 45, which have their inner end portions bent outwardly to form oppositely projecting fingers 46 and 47, as clearly shown in Fig. 3. Consequently, when the parts are in the position shown in Fig. 3, the keeper 39 will be held in snug relation with respect to the arm. However, upon movement of the collars 42 and 43 rearwardly, the keeper will be released so as to be swung upwardly into an open position under tension of the coil spring 41.

Referring now to the car device, I provide the car body A with a plate 48 adjacent the door opening, as at 49, the same plate in turn pivotally supporting a carrying arm 50 as at 51. The plate 48 further carries a pawl 52 as at 53, the pawl being adapted for seating engagement in a notch 54 of the arm 50 at certain times, whereby the latter may be held in a position shown in Fig. 5, to retain the receiving and delivering arm of the car device in proper relation to the respective arm of the ground device. At its outer end the arm 50 carries a supporting stud 55 for engagement with the receiving and delivering arm of the car device, while the said stud in turn carries an adjustable nut 56 for securely retaining the said arm in place, such as will subsequently appear.

65 The receiving and delivering arm of the

car device such as shown in Fig. 2, consists of a head 57 having a through aperture for the reception of the stud 55 of the arm 50 above referred to, while the respective end portions of the head are reduced somewhat 70 as at 58 and 59 for the purpose that will subsequently appear. The reduced portion 59 of the head 57 receives the ends of a bent strip as at 60, the intermediate portion of the strip forming a projecting arm 61. This 75 arm, like the arm 36 above referred to, carries a lateral pindle 62 intermediate its ends for pivotally supporting a movable keeper 63, while a coil spring or other similar structure 64 is mounted upon the pindle and provided with an arm 64' engaging the end of arm 61 and an arm 64'' engaging the keeper and having a normal tendency to swing the keeper 63 upwardly above the arm 61. Collars 65 and 66 are slideable on the arm 61 80 and the keeper 63, the same being connected by strips 67 and 68 which have their inner end portions bent to provide oppositely projecting triggers 69 and 70. The collars 65 and 66 also serve to normally retain the 85 keeper in snug relation with respect to the arm 61 yet are designed to permit the same to move to an open position at certain times such as will subsequently appear.

The other reduced portion 58 of the head 95 57 carries a projecting strip 71 as at 72 and a second strip 73 to lie in spaced relation to the aforesaid strip, as clearly shown in Fig. 2. The strip 71 being slightly longer than the strip 73 is provided with a movable 100 catch 74, as at 75, a coil spring 76 being provided to normally retain the said catch in an advantageous position. One end of the coil spring 76 is attached to the outer end of the catch while the other end may be 105 connected to a fastening member 77 of the strip 71, as clearly shown. By reason of the spaced relation of the strips 71 and 73, it will be noted that a ring or other mail bag 110 supporting structure may be positioned therebetween and yieldingly retained in this position through the instrumentality of the catch.

The operation of my invention is substantially as follows:—

When desiring to deliver mail from the car device and from the ground device simultaneously, the ring 78 that supports the sacks 79 to be delivered to the station is positioned upon the strip 73 of the car device between the said strip and the strip 71 behind the catch 74, while the ring 78 that carries the mail bag 79 to be delivered to the car device, is positioned on the strip 22 of the ground device, between said strip and the strip 20, behind the catch 24. When in this position, the rings will hang approximately vertical. The moving car then passes the car device between the arms 13 and 14 of the ground device, the arm 61 of 130

the car device passing through the ring 78 of the mail bag carried on the ground device, while the receiving arm 36 of the ground device passes through the ring of 5 the other mail bag. As the car device continues to move, the respective rings will be drawn in engagement with the triggers 69 and 70 of the arm of the car device and the triggers 46 and 47 of the ground device 10 thereby moving the respective collars 65 and 66, 42 and 43 rearwardly so as to release the keepers 63 and 39, permitting the latter to move into an upright or open position. When the keepers 39 and 63 move into an 15 open position, they preclude all danger of accidental dislodgment of the rings 78 thereby securely retaining the mail bags until removed by the mail clerks. As the 20 respective receiving arms pass through the rings, and the latter engage with the triggers above referred to, the ring will be forced past the catcher 24 and 74 so as to become free from the respective delivering arm.

25 From the foregoing, it will be noted the device that I have provided is entirely automatic in action, and constructed to operate in a manner whereby but little wear is subjected to the mail bags. In view of the 30 fact that the advantages and novel features of the device appear to be apparent from the foregoing, further detail description is deemed unnecessary.

In reducing my invention to practice, I 35 find that the form referred to herein as the most practical and preferred embodiment is the most efficient, but realizing that certain conditions will necessarily vary in concurrence with the adoption of my device, I 40 desire to emphasize the fact that various minor changes in the details of construction and in the proportion of parts may be resorted to when required without sacrificing any of the advantages of my invention as defined in the appended claims.

Having thus fully described my invention, what I claim as new and desire to secure by Letters Patent is:—

1. In a mail bag transferring apparatus 50 a collecting device comprising a support, an arm projecting from said support, a keeper pivotally mounted adjacent the outer end of said arm, yieldable means for retaining said keeper extending substantially at right angles to said arm, means to retain said keeper extended substantially parallel to said arm against the action of the yieldable means, and means to be actuated upon engagement with a mail bag carrying structure moving 55 upon said arm to release said keeper and permit the keeper to swing to a position at substantially right angles to the arm.

60 2. In a mail bag transferring apparatus,

a collecting device comprising an arm, a hinged keeper adjacent the outer end of 65 said arm, yieldable means normally tending to retain said keeper in an open position, movably mounted means to retain said keeper in a closed position, and abutment triggers carried by said last mentioned 70 means whereby upon engagement with a mail bag carrying structure moving upon said arm, the retaining element will move to an inoperative position and said keeper released and swung to an open position. 75

3. In a mail bag transferring apparatus, a collecting device comprising a support, an arm extending from said support, a keeper pivotally mounted adjacent the outer end of said arm, a spring connected with 80 said arm and engaging said keeper and having a tendency to force said keeper to an open position, spaced collars slidable on said arm and said keeper whereby the keeper may be normally retained in a closed position with respect to the arm, and laterally projecting triggers associated with said collars to be engaged by a mail bag carrying structure passing upon the arm to automatically release said keeper.

4. In a mail bag transferring apparatus 90 a collecting device comprising a supporting arm, a head carried by said arm, a receiving arm connected with said head, a keeper pivotally mounted upon said receiving arm, a spring engaging said keeper and having a 95 tendency to retain said keeper in an open position, means to normally retain said keeper in a closed position, and triggers on said last mentioned means to be engaged 100 with a mail bag carrying structure moving upon the receiving arm to automatically release said keeper and permit the keeper to move to an open position under tension of said spring.

5. In a mail bag transferring apparatus, 105 a collecting device comprising a support, a head carried by said support, a receiving arm connected with said head, a keeper pivotally associated with the outer end portion 110 of said receiving arm, a spring having a normal tendency to retain said keeper in an open position, spaced collars slidable on said receiving arm and said keeper to normally retain the keeper in a closed position, and laterally projecting triggers associated with 115 said collars, to be engaged with a mail bag carrying structure moving upon said arm to effect the automatic release of said keeper.

In testimony whereof I affix my signature 120 in presence of two witnesses.

LLOYD W. PRICE.
